UNITED STATES PATENT OFFICE.

ALBERT B. DICK, OF CHICAGO, ILLINOIS.

PAPER-FILE.

SPECIFICATION forming part of Letters Patent No. 447,067, dated February 24, 1891.

Application filed December 16, 1890. Serial No. 374,877. (No model.)

To all whom it may concern:

Be it known that I, ALBERT B. DICK, a citizen of the United States, residing at Chicago, in the county of Cook and State of Illinois, 5 have invented a certain new and useful Improvement in Paper-Files, of which the following is a specification.

The object of this invention is a paper-file the arches of which shall be opened for the 10 filing of papers or closed to prevent loss of papers by a positive movement in each direction, and the mechanism of which, affecting said movements, shall not be liable to be operated accidentally.

15 The invention consists in providing the movable sections of a double-arched paper-file with a connecting rod or bar provided with a cam-cut groove and operating this bar or rod, and consequently the movable sections 20 of the arches, through a swinging lever preferably carrying a friction-roller entering the cam-groove of said rod or bar.

In the accompanying drawings, forming a 25 part of this specification, Figure 1 is a plan view of a paper-file embodying my invention, showing in dotted lines the base-board with which it is usually employed. Fig. 2 is a front elevation showing the swinging lever thrown to one side of its vertical position, the 30 movable sections of the arch file being lowered and the file ready to receive papers, &c. Fig. 3 is a rear elevation showing the lever in its vertical position, the movable sections then being in the raised position closing the 35 arches of the file. Fig. 4 is a side elevation of one of the arches, looking in the direction of the arrow, Fig. 3, with certain parts in section on the plane of the line 4-4, Fig. 3.

A is the base of the paper-file usually attached by screws BB to a suitable bed or support. The base A serves to support the arches C and the movable section D D, the latter serving to complete the arches C down to the

base A when in the raised position. The arches C are adjustably supported in nipples 45 E E cast or otherwise formed on the base A, the thumb-screws F F being used to hold the arches in any desired position. The sections D D are hollow and fit loosely over posts G supported on the base A. Rigidly connecting the sections D D is a cross-bar H, which cross-bar has a depending flange or projection I, in which is cut a cam-groove J. Engaging with this groove is a friction-roller K, carried on a pintle L, projecting from one end 55 of a lever M, which lever swings on a pin N, carried by a post Q, rising from the base A.

In operation all that is necessary to prepare the file so that papers may be filed on the arches C is to swing the lever M to one 60 side, when by the action of the roller K and the cam-grooves J the sections D will be lowered. To close the sections so as to complete the arches of the file the lever is returned to its vertical position. 65

What I claim is—

1. In a double-arch paper-file, the combination, with movable sections completing the arches of the file, of a cross-bar connecting said sections, a swinging lever, and a cam-connection between said lever and cross-bar, substantially as set forth. 70

2. In a double-arch paper-file, the combination, with movable sections completing the arches of the file, of a cross-bar connecting said 75 movable sections, a cam-groove J in said cross-bar, a swinging lever M, and a friction-roller K, carried by said swinging lever entering said cam-groove J, substantially as set forth.

This specification signed and witnessed 80 this 11th day of December, 1890.

ALBERT B. DICK.
